UNITED STATES PATENT OFFICE.

SAMUEL JAMES CREW, OF YARRAVILLE, VICTORIA, AUSTRALIA.

SIGNAL DEVICE.

Application filed May 6, 1926, Serial No. 107,242, and in Australia June 23, 1925.

This invention relates to an identification device or sign which is adapted for clear visibility by daylight or in darkness and is specially applicable for use in displaying the identification numbers of automobiles. The invention may, however, also be employed for advertising and various other purposes where it is desired to clearly display a luminous sign by night and a corresponding sign by day without artificial illumination and without any alteration or manipulation of the device.

According to the invention an illuminating medium such as an electric lamp is enclosed within a box or housing which is provided with means for reflecting the artificial light through a specially constructed front sign plate which is adapted to permit of the passage of the reflected artificial light therethrough by night or in darkness and also clearly exhibits the desired number or other sign in daylight without the aid of artificial illumination.

Referring to the drawings which form part of this specification:—

Figure 1 is a front elevation showing a constructional form of the invention suitable for exhibiting a combined tail light and luminous number plate for automobiles.

Figure 2 is a contracted sectional plan, on an enlarged scale, of a device as seen in Fig. 1.

Figure 3 is a cross section on the line III III in Figure 2.

Figure 4 is a cross section on the line IV IV in Figure 2.

Figure 5 is a fragmentary detail view, in sectional plan, of a modification.

Figure 6 is a rear view of a sign unit or section, a series of which may be used to make up the required sign.

Figure 7 is a section on the line VII VII in Figure 6.

Figure 8 is a broken perspective view of a pair of said sign units or sections looked at from the front, and illustrates a mode of assembling and connecting the sections.

Figure 9 is a fragmentary rear view showing a pair of sign sections secured together in assembled position.

The invention includes a light box or housing 2 which may be constructed of sheet metal or other suitable material and is preferably of an elongated rectangular shape. At one end of this box or housing is a lamp chamber 3, which may be formed

by a casing or holder 4, and accommodates an illuminating medium such as an electric lamp 6 arranged to project the light sideways towards the opposite end of the elongated box or housing 2. A socket 7 provided with terminal pins 8 may be attached to the holder 4, to form a mounting for the lamp 6 and to supply current thereto. A reflector 9 may surround the lamp.

The lamp casing or holder 4 is preferably hingedly or detachably attached to the adjacent end of said housing 2 so as to provide for easy access to the lamp. As seen in Figures 1, 2 and 4 the lamp holder 4 may be mounted to swing about a hinge pin 11 suitably carried by the light box or housing 2 adjacent its open end. The lamp holder is fastened when in a closed position by a suitable catch, which may comprise a nut 12 working on a screw 13 which outstands from the housing and can enter an open mouthed slot 14 formed in an appropriate portion of the lamp holder.

Mounted in the opposite end of the elongated box or housing 2, that is, the end thereof remote from the lamp 6, is a mirror or other suitable reflector 16 which is preferably inclined as shown and is adapted to throw back the light rays so that they are distributed throughout the length of the housing 2 and will uniformly illuminate an identification or sign plate 17 which is preferably removably mounted at the front of the housing 2, as hereinafter described, and is visible through an opening 18 formed in the front 19 of said housing. The reflector 16 may be retained in position against the end of the housing 2 by a suitable stop or stops 21.

The back 26 of the elongated housing 2 is preferably inclined forwardly from the lamp end towards the reflector end of the housing 2, the inner or front surface 27 of the inclined back being preferably painted white or similarly treated so that the light rays thrown thereon by the lamp 6 and the reflector 16 are more effectively emitted through the identification or sign plate 17, the construction of which is hereinafter described. If desired a removable inclined back 26 may be placed within the rear of the light box or housing so that it may be withdrawn for re-painting or other purposes.

The said identification or sign plate 17 is also preferably of an elongated rectangular

shape according to the size and shape of the front of the housing 2, and, as seen in Figures 1 to 5, may consist of a sheet of metal or other suitable material of a similar nature. Portions of this sheet metal or other plate 17, corresponding to the numerals or other characters to be displayed, are cut out or removed from the plate leaving corresponding apertures 28 therethrough after the manner of a stencil plate but without the usual ties or bridge portions. The elimination of such ties is permitted by the use of a perforated metal backing material 29 to which parts 31 of the stencil-like sign plate 17 are surrounded by the apertures 28 may be secured by rivets or the like, thus leaving unobstructed apertures in front of the backing material 29. The parts 31 for disposal within the apertures 28 of the sign plate 17 may, if desired, have tongues or extensions 32 (see Figures 6 and 7) adapted to pass through slits in the backing material 29 and to be pressed backwardly against the rear surface of said backing material whereby such parts 31 are retained in position without rivets or the like.

The backing material 29 is suitably attached to the rear surface of the plate 17 so as to extend behind the apertures 28 thereof, said backing material being of such a nature as to freely pass the artificial light rays from the interior of the housing 2 when the device is used at night and also to clearly show the numerals or characters through said apertures 28 by daylight without the aid of artificial illumination. Preferably the backing material 29 consist of a sheet of metal having relatively small and closely spaced perforations therethrough such sheet being painted or coated white or other suitable color on its front face so that the parts of the backing material showing through the apertures 28 in the front plate 17, form distinctly visible identification characters when viewed in daylight, the perforations of the backing material being adapted to clearly emit the artificial light from the interior of the housing 2 when the device is used at night or in darkness.

The apertured sign plate 17 may consist of a single sheet or strip of metal with the backing 29 suitably secured to the rear face thereof, so as to extend across the openings 28 therein, or, if desired, the sign plate and backing material may comprise a series of sections 17^a and 29^a (see Figures 6 to 9) adapted to be slidably engaged with each other and accommodated at the front of the housing 2. Each sign plate section 17^a may have inturned vertical edge portions or lips 33 engageable with corresponding edge portions of the other sign plate sections in order to form suitable lapped joints, as shown in Figures 8 and 9, whereby a plurality of the sections 17^a may be assembled in

any required formation or sequence. The individual numerals or characters of a sign or the like may thus be readily interchanged so that any desired combination of numerals or characters may be assembled without the necessity of cutting a new sign plate 17. When the device is used for displaying the identification number of an automobile it may be desirable to prevent, or to render difficult, the changing of the assembled sections 17^a as a deterrent against fraudulent or unauthorized changing of the number. For this purpose each section 17^a may be provided, preferably adjacent its corners, with projecting wires 34 which may be twisted, soldered or otherwise fastened to corresponding wires of adjoining sections as indicated at 35 in Figure 9. Instead of using such wires the sign plate sections may be secured together by crimping or flattening the inturned lips 33 of the interengaged sections.

The upper and lower edge portions 36 of each section 17^a may be bent around and backwardly against the corresponding backing material section 29^a whereby the latter will be securely held in proper position.

The apertured sign plate with its backing material is preferably bodily removable from the front of the light box or housing 2 and for this purpose guideways 37 are preferably formed at the front of the housing along the top and bottom thereof, one end of these guideways being open to permit of the insertion and removal of the apertured sign plate and its backing material. A handle 38 may also be provided at one end of the sign plate to facilitate its insertion and removal as above mentioned.

The outer or front surface of the apertured sign plate 17 is preferably painted or coated black around the apertures 28 forming the numbers or other characters which are formed, so as to render more prominent the backing material 29 showing through said apertures.

When the device is to be used as a combined tail light and luminous sign or number indicator on automobiles and the like, one end of the apertured sign plate 17 or an end section 17^a thereof may be provided with a red colored transparent plate 41 which is preferably disposed adjacent the aforesaid lamp 6 and at the front of the housing 2 so that the light rays projected sidewardly by said lamp 6 are also thrown forwardly from the back of the housing through the colored transparent plate at one end of the illuminated sign. The front 19 of the housing 2 is provided with an opening to accommodate the plate 41. It is thus not necessary to provide two lenses for the lamp employed in accordance with this invention, as is the case with the ordinary external tail lamps commonly employed on 130

automobiles and which require to project the light sidewardly on to the front of the exposed number plate as well as at right angles through the coloured glass lens.

5 The tail light plate 41, or a red coloured lens 44 suitably mounted upon a front wall 46 around an opening therein, may, if desired, be disposed in direct alignment with the lamp 6 as seen in Figure 5 in order that

10 the maximum brightness of the tail light will be ensured without detracting from the illumination of the sign plate 17. A reflector 9 may partially surround the lamp 6, the reflector having a gap as at 9^a to

15 permit direct illumination of the tail light plate or lens.

According to the modification illustrated in Figure 5 instead of the lamp casing or holder 4 being hingeably mounted to the light box or housing it is adapted to slide into and out of the said housing. In such instance the holder 4 may have side members 4^a which are slidable within the guideways 37 extending along the top and bottom of 25 the housing 2 while the opposite side member 4^b of the holder 4 may be a sliding fit within the housing. Suitable means such, for example, as a screw 13 and nut 12 as previously mentioned may be provided to 30 prevent accidental withdrawal of the lamp holder 4 which may be fitted with a suitable handle 4^c.

The invention provides a simple, inexpensive and highly efficient device which 35 owing to the concentration of the light rays within the enclosing light box or housing 2 and the uniform and effective distribution of such light through the apertured sign

plate 17, greatly increases the visibility of the identification number or sign by night 40 as compared with existing arrangements for the illumination of automobile tail lights and the like. In addition, the lamp 6 and other parts are effectively protected from damage, and the device provides a light, 45 durable, and compact construction constituting a unit which may be readily placed on an automobile or in other desired positions, and may be readily converted to suit different uses by merely interchanging the apertured sign plate so as to exhibit the desired 50 sign.

Having now described my invention what I claim as new and desire to secure by Letters Patent is:—

55 A sign indicator for use in signs, including a sign plate formed with apertures arranged to simulate characters and a strip of perforated backing material, said sign plate and perforated backing material being 60 each made up of a series of sections, the sections of the sign plate being each provided at opposite edges with inturned vertical edge portions of hook formation designed to interengage with corresponding edge portions 65 of adjoining sections, the perforated backing material sections being adapted for attachment to the back of the respective sign plate sections and held in position thereon by bending the upper and lower edge portions 70 of the respective sign plate sections rearwardly against the corresponding sections of the perforated backing material.

In testimony whereof I affix my signature.

S. J. CREW.
